VALVING SYSTEM FOR WATER SOFTENERS
John W. Timmons, 909 E. Main St., Greenville, Ohio
Filed Nov. 9, 1962, Ser. No. 236,531
7 Claims. (Cl. 137—599.1)

This invention relates to a valve, and more particularly to a valve of the type which is adapted to be used in conjunction with water softening systems.

An object of the invention is the provision of a unitary control mechanism for original installation or for application to existing installations of water softeners for providing complete, automatic determination of softening, backwash, brining, slow rinse, fast rinse, and regenerative cycles of the system.

Another object of the invention is the provision of a simplified automatic cyclic regeneration control device of compact form embodying a minimum number of movable control elements, utilizing existing fluid pressure and pressure varying means for determining the sequence of operation, eliminating necessity of any hand operation or control, or employment of complicated driven cams or other mechanisms.

A further object of the invention is to provide a valve which includes a plurality of solenoid-controlled valving means; said valve being adapted, in conjunction with a suitable timing means, to automatically control the flow of raw water through a softening tank, thence to an outlet for usable, softened water; or for diverting the flow of raw water from the softening tank into a brine tank and the subsequent flow of brine into the water softener for re-activating the water-softening crystals of the water softener; for effecting automatic rinsing of the crystals after re-activation; and for automatically recharging the brine tank with water for a subsequent cycle.

Still a further object of the invention is to provide a valve which includes various inlet and outlet ports which may be conveniently connected to the various water lines leading to a water softener, brine tank, outlet line and softened water line whereby to effectively automate the various operating, charging, rinsing, etc. cycles.

Other objects and advantages of the present invention will be readily apparent by reference to the following specification taken in connection with the accompanying drawings, illustrative of one embodiment thereof, and it will be understood that any modifications of the specific structural elements shown and described may be made, within the scope of the appended claims without departing from or exceeding the spirit of the invention.

These and other objects are attained by the means described herein and as disclosed in the accompanying drawings in which:

FIG. 1 is a plan view of a typical water softener system utilizing a cyclic control valve embodying the teachings of the invention.

FIG. 2 is a vertical section through the valve of FIG. 1.

FIG. 3 is a diagrammatic view of the valve of FIG. 2, illustrating the relationship of the various elements thereof during a normal softening or filtering cycle wherein raw water is directed to the inlet of the softener tank and softened water from the softener tank is directed to the house lines.

2

FIG. 4 is a view similar to FIG. 3, showing the valve elements in position for a backwash cycle.

FIG. 5 is a view similar to FIG. 3, showing the valve elements in position for the brining and slow-rinse cycles.

FIG. 6 is a view similar to FIG. 3, showing the valve elements in position for the fast-rinse cycle.

FIG. 7 is a view in section of a conventional normally open pressure actuated valve forming an element of the system.

10 As has been pointed out in connection with the enumeration of the objects of the present invention, I have provided a novel, compact and improved unitary valve or control mechanism for use as part of an original installation or alternatively, for application to existing water softener installations. Such installations, as commonly known in the prior art for continuous softening of hard or "raw" water, normally comprise a tank 10 containing a body of water-softening and filtering material and a brine tank 12 intermittently employable to clean and regenerate the condition of the tank 10 containing water softening material. It will be understood that these parts, like the supply line for the raw or untreated water and the distribution line or system for the treated or softened water may be of any conventional form, and as they, in themselves, form no part of the present invention.

20 In the drawings, similar reference characters are employed to denote corresponding parts throughout the several views. The numeral 20 denotes generally the valve of the present invention which includes a central body portion A and side body portions B and C, each of which latter portions is provided with axially aligned internally threaded pipe-receptive sockets 22-24 and 26-28, respectively. Socket 22 constitutes the raw or hard water inlet port of the valve which is adapted to be connected to 25 a source of raw water, under pressure, via supply pipe 21. Socket 24 constitutes the raw water outlet port of the valve which is adapted to be connected to the inlet 19 of water softener tank 10 via pipe 23.

30 Socket 26 constitutes the water outlet port of the valve which is adapted to be connected to a soft water delivery pipe 25. Socket 28 constitutes the soft water inlet port from the water softener tank to which it is adapted to be connected by means of pipe 27.

35 With further reference now to FIG. 1, the numeral 30 denotes a drain line connected to drain outlet port 32 in the central body portion A; and the numeral 34 denotes a brine line interconnecting brine port 38 of the valve with the brine tank 12.

40 The numerals 40 and 50 denote generally solenoids which are suitably secured to and carried by the central body portion A. The operation or actuation of the aforesaid solenoid is controlled by an electric timer 60 via conductors 42-44 and 52-54, respectively.

45 The interior of body portions B, A and C are provided with internal passageways and chambers, whereby during the normal softening cycle, note FIG. 3, the raw water from inlet port 22 will pass through conduit 70, conduit passage 72 into chamber 74 thence to conduit 76 and out through port 24 to the softener tank 10 via pipe 23 (FIG. 1).

55 Treated or softened water from tank 10 will pass through pipe 27 to valve port 28, conduit 78, into chamber 80,

through conduit passage 82 into conduit 84 and out through port 26 to distribution pipe 25.

Chambers 74 and 80 are provided with diaphragms 90 and 92, respectively, which comprise separating walls defining sub-chambers 91-93 and 79-81, respectively. Diaphragms 90 and 92 are operatively connected by pistons or actuator members 931 and 95 to poppet valves 94 and 96, respectively.

The numeral 100 denotes a by-pass conduit which inter-connects conduits 70 and 84; and the numeral 114 denotes another by-pass conduit which inter-connects portions of conduits 84 and 76.

During a normal softening cycle raw water from conduit 70 is precluded from entering by-pass conduit 100 by reason of poppet valve 94 engaging valve seat 97 in the conduit 70 end of by-pass conduit 100.

During the softening cycle the solenoids 40 and 50 are de-energized and valve elements 110 and 120 are disposed in closed position for preventing a flow of water through drain conduit 108, which is in open communication with drain port 32.

A check valve 112 in by-pass conduit 114 prevents a back-flow of raw water into conduit 114.

With further reference to FIG. 3, it will be noted that flow through drain conduit 108 is controlled by valve member 110 under the control of solenoid 40, and that when element 110 is in a closed position there is no flow of water from chamber 74 to conduit 108, and that water flowing through bleeder passage 109 from sub-chamber 91 to sub-chamber 93 is impounded so that an equalized pressure condition is built up in said chambers on opposite sides of diaphragm 90.

Due to the presence of piston rod 931, the pressure sensitive area of the diaphragm in sub-chamber 93 is somewhat in excess of the opposed area in sub-chamber 91, effecting and insuring movement of poppet valve 94 to the left, as illustrated. The numeral 111 denotes an additional bleeder conduit or passage extending between and in open communication with conduit 70 and sub-chamber 93 for additionally insuring that line pressure will be provided in sub-chamber 93, which will maintain the parts in the operating positions illustrated in FIG. 3, even in the event of a power failure.

The foregoing water softening cycle may continue for a period of from one to many days, depending upon the capacity of the softener tank 10 and the use-demands placed upon the system. Timer 60 will be pre-set whereby to terminate the softening cycle for initiating a back-wash cycle which will occur incident to energization of solenoid 40, through timer 60, resulting in opening valve element 110 which will permit diaphragm 90 to be flexed to the right, as illustrated in FIG. 4, for shifting poppet valve 94 away from seat 97 to engage seat 71. Raw water from conduit 70 will be diverted through conduit passage 97 into conduit 100 into conduit 84, conduit passageway 82, chamber 80, conduit 78, thence out port 28, into pipe 27 for thereby effecting a reverse flow through softener tank 10, it being understood that during such reverse flow water will flow from port 19 of the softener tank through pipe 23 into valve port 24 through conduit 76, chamber 74, bleeder passage 109, conduit 108, thence out drain port 32.

As soon as valve element 110 has been opened, as in FIG. 4, the pressure of raw water within chamber 74 will force the diaphragm 90 to the right for actuating poppet valve 94, thereby effecting a back-wash or reverse cycle of raw water through the softener tank. The foregoing cycle should be continued until the iron and sediment have been removed from the mineral bed of the softener tank; in actual practice it has been found that a ten minute back-wash cycle is quite satisfactory.

At the conclusion of the back-wash cycle, solenoid 40 remains energized, and solenoid 50 is also energized, whereby each of valve elements 110 and 120 will be opened as illustrated in FIG. 5. When valving member 120 is opened, the raw water from conduit 70 will be

diverted into by-pass conduit 100 to conduit 84, thence into by-pass conduit 114 and past venturi 150 which will develop a suction in brine line 116 for providing a mixture of raw water and brine past check valve 112 into conduit 76; thence through valve port 24 to softener tank 10 via pipe 23.

Water from the outlet 9 of the softener tank will be conducted through pipe 27 to valve port 28, thence through conduit 78, chamber 80, around diaphragm 92, through bleeder passage 200, thence into drain conduit 108 to drain port 32. It will be noted that diaphragm 92 will be shifted to the left and maintained in that position for disposing poppet valve 96 in fluid closing relationship with respect to conduit passage 82 while providing free access through passage 83 between conduits 84 and 114. The mixture of brine and raw water entering conduit 76 will apply a pressure against diaphragm 90 for maintaining it in the position illustrated in FIG. 5 whereby poppet valve 94 will be maintained in closed relationship with respect to conduit passage 72.

A mixture of brine and raw water is thus permitted to pass through the softener tank for a period of 10 minutes, or until such time as the brine tank has been completely emptied, after which further flow of raw water through the softener tank will result in the mineral bed of the softener tank being subjected to a rinsing action.

Suitable conventional means, not illustrated, such as, by way of example, a conventional air check, may be provided in association with the brine tank for preventing air from being drawn from the brine tank into the softener; and for permitting raw water to flow into the top of the softener tank for rinsing the salt and brine from the mineral bed of the softener tank.

The next automatic cycle to which the valve is subjected is the fast-rinse and brine tank filling cycle which will automatically occur when solenoid 40 is de-energized for closing valve element 110, as in FIG. 6, which will result in diaphragm 90 being snapped to the left, for shifting poppet valve 94 whereby to open conduit passage 72 and close conduit 100 for thereby establishing a flow of raw water through conduit 70, conduit passage 72, into chamber 74, to conduit 76, through port 24, through pipe 23, to intake 19 of the softener tank 10; thence from outlet 9 of the softener tank through pipe 27 to port 28, thence through conduit 78, chamber 80, around diaphragm 92, via bleeder passage 200, into conduit 108, and out drain port 32. During this operation check valve 170 will be unseated for establishing a flow of water into conduits 84 and 114 for introducing softened water from tank 10 through conduit 114 into brine conduit 116; it being understood that the pressure of fluid within conduit 114 is less than that required to unseat check valve 112 during the cycle illustrated in FIG. 6. The foregoing cycle requires as much time as is necessary to fill brine tank 12 with water and simultaneously with the filling of the brine tank water from the softener will pass upwardly through the valve around diaphragm 92 and thence out drain port 32. When the brine tank has been filled timer 60 will de-energize solenoid 50 for producing the relationship of elements illustrated in FIG. 3, viz., with each of solenoids 40 and 50 de-energized for placing valve elements 110 and 120 in closed position.

Each of chambers 74 and 80 may be considered primary diaphragm chambers.

To summarize, it will be noted that the subject valve, when timer actuated, will automatically terminate the softening cycle and initiate a series of cycles for regenerating and cleaning the zeolite or other water-softening material housed within tank 10.

The first phase of the regenerating cycle is that of effecting a back-wash or reversal of flow, injecting the raw water into the bottom of the softener tank and flushing out the tank from bottom to top with the discharged

medium flowing to drain, thus removing free impurities and sediment from the mineral bed within the tank.

This operation is accomplished by energizing solenoid 40 to lift valve 110 as shown in FIG. 4. With the valve so lifted, there will be a pressure drop in chamber 93, permitting diaphragm 90 to flex to the right as viewed in FIG. 4. This moves poppet valve 94 to close off passage 72 and divert the incoming flow from passage 70 by way of now opened passage 100 and through 84, 82, 80, 78, 28, through pipe 27 (FIG. 1) to the normal outlet 9 of the softener tank, thus reversing the direction of flow through tank 10.

At the same time, fluid from the normal inlet 19 of tank 10, as indicated by the arrows, will discharge through 76, 74, 109, 108, drain port 32 and drain pipe 21. During this flow, pressure is maintained in sub-chamber 91 holding poppet valve 94 in its passage interrupting position. It will be noted that since the conduit 100 discharges into conduit 84, during this back-wash cycle the input raw or "hard" water is automatically by-passed to port 26 to enable the householder or user of the system to obtain water during this back-wash cycle. This cycle may be maintained, for example, for approximately ten minutes for effecting the basic cleaning or flushing out of the softener tank.

Thereafter, solenoid 50 is activated raising valve 120 so that the parts then occupy the position indicated in FIG. 5, both valves 110 and 120 being in their open position. The pressure drop thus effected in sub-chamber 79 will result in deflection of diaphragm 92 to the left as viewed in FIG. 5 moving poppet valve 96 to shut off flow of the raw or hard water into the softener tank outlet connection and coupling this connection by way of 80, 108 to drain. At the same time, movement of valve 96 couples the raw water input through 114 to 76 and thus to the normal softener tank inlet 19.

Brine from the brine tank 12 will be injected along with the raw water into the top of the softener tank and will pass outwardly from the bottom of the softener tank, thence upwardly through 78, 80, 108 out the drain line. This cycle may be continued, for example, for a period of 20 minutes for effecting a desired brining and rinsing.

At the conclusion of this operation it is then desirable that a final fast-rinse be given the system before cutting over to the normal soft water flow to the distribution system is initiated.

This is effected by timer release of solenoid 40 and closing of valve 110 as shown in FIG. 6, again impounding the fluid pressure in sub-chamber 93, moving poppet valve 94 to seal off passage 100 and permit flow of the raw input water through 74, 76 to the softener tank. As valve 120 is still in the open position, poppet valve 96 seals off the direct flow from 78 to 84, the main discharge continuing to be 78, 80, 108 to drain, although adequate temporary supply of water to distribution outlet 84 may be supplied from 78 through the one-way check valve 170. At the same time, this flow will be effective through conduit passage 114, 116 to recharge the brine tank, pressure in 76 accentuated by the check valve spring holding valve 112 closed and sealing off the outlet from 114.

The foregoing cycle requires as much time as is necessary to fill the brine tank, after which the timer will de-energize solenoid 50 and valve 120 will close shutting off flow from its side of the casing into the drain line, poppet valve 96 will open, re-establishing the normal flow from the softener tank through 78, 80, 82, 84 to the soft water distribution system, as in FIG. 1.

With reference now to FIG. 2, it will be noted that those portions of diaphragms 90 and 92 which extend beyond their respective chambers 74 and 80 comprise gaskets between the adjacent faces of body portions B-A and A-C, it being understood that side portions B and C may be

securely, though releasably, secured to center portion A by suitable bolts, not illustrated.

From the foregoing description taken in connection with the drawings, the construction and operation of the present, improved, automatic control for use in connection with softener and brine tank water treating mechanisms should be readily understood, and it will be seen that there has been provided a simple, efficient, and effective mechanism for causing adequate periodic cleaning and regenerative action as respects the softener tank operation.

With particular reference now to FIGS. 3-6, the letter Q denotes a passageway interconnecting by-pass conduit 114 in advance of venturi 150 with side 93 of diaphragm chamber 74. The letter L denotes suitable means such as a conventional normally open fluid actuated valve in conduit 109, which valve means will be closed over rendered effective by pressure in passageway Q for closing conduit 109 during the brining cycle illustrated in FIG. 5 and during the fast rinse cycle illustrated in FIG. 6. When said means L has thus been activated by the fluid pressure in by-pass conduit 114, flow of fluid from conduit 76 and sub-chamber 91 to drain conduit 108 via conduit 109 is effectively prevented.

The valve means L may be of any suitable construction to effect the operation above described. The illustrated valve is generally designated L'. The structure shown consists of a diaphragm casing d having the inlet at one side for connection with the passageway Q and having upon the opposite side of the flexible diaphragm d' a poppet valve stem s which extends into a valve housing h which may be interposed in the conduit 109. The valve element v is normally maintained in raised or open position with respect to the seat d', by the spring s' which resists the downward movement of the diaphragm d'. As will be readily apparent, when fluid under pressure passes through the passageway Q into the valve casing d the diaphragm d' will be forced downwardly and conduit 109 will be closed.

What is claimed is:

1. A regenerating control for water softeners of the type including a filtering softener tank and a brine tank, said control comprising a casing having inlet and discharge ports adapted to be connected, respectively, to a supply source and a distributing conduit, and additional ports connectible, respectively, to the inlet and outlet of the softener tank, a primary conduit in the casing extending from the supply inlet port to the softener tank inlet port, a secondary conduit extending from the softener tank outlet port to the distributing conduit port, said casing having two chambers each divided into two parts, said primary conduit including a first part of one chamber and said secondary conduit including a first part of the second chamber, a branch conduit connecting said primary conduit with the secondary conduit, the connection of the branch with the secondary conduit being between the secondary conduit chamber and the distributing conduit port, valve means in said primary conduit alternately positionable to determine flow from the supply inlet port to the tank inlet port or to the branch conduit, a flexible diaphragm in each chamber between the two parts thereof, connection means between said valve means and the adjacent side of the diaphragm in said one chamber, a drainage conduit in said casing extending between the two other parts of said two chambers, a bypass conduit connecting said secondary conduit with the primary conduit at a location between the said first part of one chamber and said tank inlet port, a second valve means in said secondary conduit, said second valve means being alternately positionable to connect either the soft water tank outlet port or the bypass conduit with the distributing conduit port and branch conduit, means connecting the second valve means with the adjacent diaphragm, means for introducing fluid from said brine tank into fluid flowing through said bypass conduit to said primary conduit, a check valve in said bypass conduit between the last means and the primary conduit and opening toward the primary

conduit, said drainage conduit having a drain outlet between said corresponding halves of the chamber, a bleeder passage between the two parts of each chamber across the adjacent diaphragm, passage means connecting the primary conduit between the valve means therein and the supply inlet port with that part of the chamber of the primary conduit to which said drainage conduit extends, means associated with the bleeder passage of the primary conduit chamber for closing such bleeder passage responsive to a predetermined high pressure in the bypass conduit, check valved passage means bypassing the valve means in the secondary conduit arranged to permit flow from the softener tank outlet port to the distributing conduit port but preventing flow in the reverse direction, the two said valve means being positively reciprocated to control flow through their respective conduits by fluid pressure applied to both sides of their respective diaphragms, and electrically actuated valves in said casing controlling flow through said drainage conduit and having said drain outlet located therebetween.

2. The invention according to claim 1, wherein said means associated with the bleeder passage of the primary conduit chamber for closing such bleeder passage responsive to a predetermined high pressure in the bypass conduit is a normally open valve means in the bleeder passage of the primary conduit chamber which is made operative to block said flow of fluid in the bleeder passage of the primary conduit chamber only during brining and rinsing operations of the system.

3. A control for water softeners of the type including a softener tank with inlet and outlet connections and a brine tank, said control comprising a casing having a central body portion and opposite side body portions, one side body portion having a supply inlet port for connection to a water supply source and an outlet port for connection to a softener tank inlet port, the other side body portion having a discharge port for connection to a soft water delivery conduit and a soft water inlet port for connection to the softener tank outlet, a primary conduit in said one side body portion extending from said supply inlet port to said outlet port, a secondary conduit, said secondary conduit being in said other body portion and extending from said discharge port to said soft water inlet port, said casing having two chambers therein each divided in halves, one half of each chamber being in said central body portion and each body side portion having the other half of a chamber therein, a flexible diaphragm in and dividing each of said chambers into the said halves, said primary conduit including a half of one chamber, said secondary conduit including a half of the other chamber, a branch conduit connecting said primary conduit with the secondary conduit, the connection of the branch with the secondary conduit being between the secondary conduit chamber and the discharge port, valve means in said primary conduit alternatively positionable to determine flow from the supply inlet port to the tank inlet port or to the branch conduit, connecting means between said valve means and the adjacent side of the diaphragm in said one chamber, a drainage conduit in said central body portion of the casing extending between the corresponding halves of the chambers in the central body portion, a bypass conduit connecting said secondary conduit with the primary conduit at a location between the first mentioned half of said one chamber and said outlet port, a second valve means in said secondary conduit, said second valve means being alternatively positionable to connect either the soft water inlet port or the bypass conduit with the discharge port and branch, means connecting the second valve means with the adjacent diaphragm, means for introducing fluid from said brine tank into fluid flowing through said bypass conduit to said primary conduit, a check valve in said bypass conduit between the last means and the primary conduit and opening toward the primary conduit, said drainage conduit having a drain outlet means, a bleeder passage between the two parts of each chamber across the adjacent motor means, passage means connecting the primary conduit between the valve means therein and the supply inlet port with the other part of the one chamber, means associated with the bleeder passage related to said primary conduit for closing this said bleeder passage responsive to a predetermined high pressure in the bypass conduit, passage means bypassing the valve means in the secondary conduit permitting flow from the soft water inlet port to the discharge port but preventing flow in the reverse direction, the two said valve means controlling flow through their respective conduits in response to said motor means and valve means in the drainage conduit for selectively

tween the two halves of each chamber across the adjacent diaphragm passage means connecting the primary conduit between the valve means therein and the supply inlet port with that half of the chamber of the primary conduit in the central body portion, means associated with the bleeder passage of the primary conduit chamber for closing such bleeder passage responsive to a predetermined high pressure in the bypass conduit, check valved passage means bypassing the valve means in the secondary conduit arranged to permit flow from the soft water inlet port to the discharge port but prevent flow in the reverse direction, the two said valve means being positively reciprocated to control flow through their respective conduits by fluid pressure applied to both sides of their respective diaphragms, and electrically actuated valves in said central body portion controlling flow through said drainage conduit and having said drain outlet located therebetween.

4. The invention as defined by claim 3, wherein said diaphragms are peripherally interposed between and engaged by opposing surfaces of said central body portion and the opposite side body portions and form seals between said confronting surfaces.

5. A control for water softeners of the type including a softener tank with inlet and outlet connections and a brine tank, said control comprising a casing having a supply inlet port for connection to a water supply source and an outlet port for connection to a softener tank inlet port, said casing also having a discharge port and a soft water inlet port for connection to the softener tank outlet, a primary conduit in said casing extending from said supply inlet port to said outlet port, a secondary conduit in said casing extending from said discharge port to said soft water inlet port, said casing having two chambers therein each divided into parts, fluid pressure responsive motor means dividing each of said chambers into the said parts, said primary conduit including a part of one chamber, said secondary conduit including a part of the other chamber, a branch conduit connecting said primary conduit with the secondary conduit, the connection of the branch with the secondary conduit being between the secondary conduit chamber and the discharge port, valve means in said primary conduit alternatively positionable to determine flow from the supply inlet port to the tank inlet port or to the branch conduit, connecting means between said valve means and the adjacent side of the motor means in said one chamber, a drainage conduit in said casing extending between the parts of the chambers divided by said motor means from said primary and secondary conduits, a bypass conduit connecting said secondary conduit with the primary conduit at a location between the first mentioned half of said one chamber and said outlet port, a second valve means in said secondary conduit being alternatively positionable to connect either the soft water inlet port or the bypass conduit with the discharge port and branch conduit, means connecting the second valve means with the adjacent motor means, means for introducing fluid from a brine tank into fluid flowing through said bypass conduit to said primary conduit, means in said bypass conduit between the last means and the primary conduit and permitting flow toward the primary conduit while preventing flow in the other direction, said drainage conduit having a drain outlet means, a bleeder passage between the two parts of each chamber across the adjacent motor means, passage means connecting the primary conduit between the valve means therein and the supply inlet port with the other part of the one chamber, means associated with the bleeder passage related to said primary conduit for closing this said bleeder passage responsive to a predetermined high pressure in the bypass conduit, passage means bypassing the valve means in the secondary conduit permitting flow from the soft water inlet port to the discharge port but preventing flow in the reverse direction, the two said valve means controlling flow through their respective conduits in response to said motor means and valve means in the drainage conduit for selectively

controlling flow from each of said chambers to the drain outlet means.

6. The invention as defined in claim 5, wherein the valve means in the drainage conduit comprises electrically actuated valves one such valve being located between said drainage outlet means and the chamber associated with said primary conduit and another valve located in the drainage conduit between the drainage outlet means and the chamber associated with said secondary conduit.

7. The invention as defined in claim 5, wherein said fluid pressure responsive motor means comprises a resilient diaphragm.
